UNITED STATES PATENT OFFICE.

SAMUEL COE, OF JERSEY CITY, NEW JERSEY.

STRIPING MACHINE.

Application filed February 18, 1925. Serial No. 9,918.

My invention relates to improvements in striping machines and has for its particular object to provide a machine which will automatically make a straight lining or striping on walls and ceilings. The device is intended to provide a machine which will automatically make a straight line in any color or with any vehicle and by which a straight line may be produced on walls and 10 ceilings with less time and expense than is now necessary by doing the striping by hand.

Further objects of the invention will be apparent from the drawings in which—

15 Figure 1 is a front view of my improved device,

Figure 2 is a side elevation,

Figure 3 is a rear view,

20 Figure 4 is a top plan view of my improved device,

Figure 5 is a view partly in section showing the operative parts,

Figure 6 is a separate view of the outside shaft actuating the device,

25 Figure 7 is a detail view of the platform carrying the paint medium,

Figure 8 is a detail view of the brush holder, in which any sized brush can be used, and

30 Figure 9 shows the guide for regulating the distance of the machine from the edge of the wall or moulding where the striping is to be applied.

It is obvious that in striping walls or ceilings or other objects by hand, it is impossible to produce a stripe of uniform straightness and width, especially where said stripe has to be continued for a considerable length and I have attempted in this machine to 40 devise an automatic means for producing such a stripe of uniform straightness and width.

A is the paint holder of cylindrical form having the right angled bottom B. Within the holder A is placed the piston C having the rod D mounted at its lower end in any suitable manner in the bottom of the tube R and a supplementary head E on which is positioned the cog F whose function will be hereinafter described. Meshing in the cog F is the small cog wheel G borne on the upper end of the shaft H which shaft carries at its lower end a small cog wheel G'. The bottom of the device B is supported on 50 the pair of small wheels K and L. The

wheels K are joined by the endless screw M which meshes into the cog wheel G' so as to actuate in turn the cog wheel G and the wheel E. The wheel E moves the threaded rod D which in turn forces the piston C to 60 descend, thus forcing a minute quantity of the paint or other tinctorial medium from the mouth of the bottom of the holder B. The rings P are supports for the bottom of the holder B. The bottom of the holder 65 is made as the drawing clearly shows with the cylindrical tube Q fitting the orifice R, the member Q terminating in a right angle trough S to which is attached the brush member T by the holding member W.

In order to make stripes of different widths, guides of different widths must be provided, a guide for a specific width being shown as X. The size of the brush may be varied but the width of the stripe will 70 be determined not exactly by the width of the brush but by the size of the orifice in the guide X which has been marked in the drawing as Z and a separate guide is necessary for every width of stripe.

The device in Figure 9 is an attachment to the bottom of the striping device so that the striping device may be moved at any fixed distance from the edge of the wall or moulding and will remain at this distance during the operation. In the bottom of the cylinder B is provided a tooth T' which fits into the orifices O of the guide GG. The guide GG has the spring plate U having the orifices OO and in order to adjust the distance from 85 the edge of the wall or moulding, the plate U is fitted into the tooth T' on the bottom of the device. It is also evident that the size of the orifice Z' may be adjustable according to the fluidity and the particular 90 nature of the tinctorial medium being employed. As it is evident, a smaller orifice may be necessary with a thin quickly flowing liquid than with a liquid having a heavier and more resistant body.

The piston C moves in the vertical guide C² so that any rotation of the wheel E produces a direct downward movement of the piston C. A leather washer C¹ is provided for the bottom of the piston C so as to 105 effectually seal the top of the column of the paint vehicle.

Having thus fully described my invention, what I claim is:—

1. In a paint striping machine, the combi-

- nation of a cylinder, a piston in said cylinder, actuating geared means on the outside of said cylinder, said actuating means co-operating with the movement of said piston so as to force an even line of a tinctorial medium from the mouth of said cylinder.
2. In a striping machine, a cylinder containing a paint medium, a piston in said cylinder, a threaded rod in said piston, an independent wheel member on said threaded rod, said piston being actuated by the forward movement of said cylinder so as to
- 10

impel a straight line of a tinctorial medium from the mouth of said machine. 15

3. In a striping machine, a cylinder containing the paint medium, a piston fitting said cylinder, a threaded member fitting said piston and propulsive means carried by said machine by which an even line of tinctorial medium is expelled from the mouth of said cylinder as said cylinder is actuated by said propulsive means. 20

In testimony whereof I affix my signature.

SAMUEL COE.
